CLAIM

The ornamental design for a magazine rack, as shown and described.

DESCRIPTION

FIG. 1 is a perspective view of a magazine rack showing my new design;

FIG. 2 is a front elevational view thereof;

FIG. 3 is an end view thereof, the opposite side being a mirror image of the end shown;

FIG. 4 is a top plan view thereof shown in a folded position; and,

FIG. 5 is a bottom view thereof.
